J. L. CREVELING

ELECTRIC REGULATION

Original Filed April 9, 1917

UNITED STATES PATENT OFFICE.

JOHN L. CREVELING, OF WHITE PLAINS, NEW YORK, ASSIGNOR TO GOULD COUPLER COMPANY, A CORPORATION OF NEW YORK.

ELECTRIC REGULATION.

Application filed April 9, 1917, Serial No. 160,718. Renewed April 25, 1923.

To all whom it may concern:

Be it known that I, JOHN L. CREVELING, a citizen of the United States, residing at White Plains, in the county of Westchester 5 and State of New York, have invented new and useful Improvements in Electric Regulation, set forth in the annexed specification and drawing, forming a part thereof.

My invention pertains to that class of 10 electric regulation wherein a dynamo electric machine is automatically regulated in a pre-determined manner, and has for a particular object to provide means whereby the same may be automatically regulated within narrow 15 limits and wherein the regulation will be performed in such manner as to be appropriate for the conditions under which the dynamo is operated.

My invention is particularly applicable to 20 systems wherein a dynamo operating as a generator with variable speed of rotation of its armature is used to charge a storage battery and operate lamps or translating devices in conjunction therewith which are supplied by the battery when the dynamo is inoperative. More specifically, one of the 25 principal objects of my invention is to provide a system wherein a generator will be automatically regulated under certain conditions 30 in response to fluctuations in the current supplied by the generator to a storage battery or other source of counter-electro-motive force capable of reversing the direction of current through the regulating apparatus, and wherein, upon such reversals, the proper operation of the generator will not be interfered with.

In the drawing, Fig. I is a diagrammatic representation of one type of system 40 chosen to show one embodiment of my invention; Fig. II is a diagrammatic representation of a portion of a system somewhat similar to that shown in Fig. I and possessing an additional feature not shown in Fig. I but 45 comprehended by my invention; and Fig. III shows a modification that may be made in the system of Fig. II.

Referring particularly to Fig. I, 1 represents a dynamo or generator driven at variable and intermittent speeds, in this instance indicated as a plain shunt machine, provided with the field coil 2 having in operative relation thereto any suitable type of regulating element or device, in this instance indicated 55 as a carbon pile 3 in series with said coil.

It will therefore be evident that the operation of the generator may be regulated by proper manipulation of the pile 3. The pile 3 rests at one extremity against the abutting member 4, which may be made adjustable if 60 desired. The other end of the pile may have variable pressures exerted thereupon by means of the short arm 5 of the bell-crank lever, provided with the long arm 6 and pivotally supported as indicated at 7. 8 is a 65 movable weight carried by the lever 6, which may have its position altered for the purpose of adjustment; while 9 is a dash-pot cooperating with the lever 6 to prevent too sudden movement thereof. The lever 6 has 70 pivotally united therewith a rod of brass or other non-magnetic material 10, carrying a core of iron or other magnetic material 11, surrounded by the coils or solenoids 12 and 13. The lower extremity of the core 11 is 75 operatively connected with the dash-pot indicated at 14, which may serve as a guide and prevent too sudden movement being imparted to the core 11. 15 is a solenoid provided with the core 16, as indicated in dotted lines, which carries at its upper extremity a rod of non-magnetic material 17 which serves as a guide for one end of the said core 80 while the other end of the core is provided with a dashpot 18 which serves as a guide and prevents too sudden movement thereof. The positive terminal of the generator 1 is connected by wire 19 with one side of a suitable automatic switch 20, the opposite side of which is connected as by wire 21 with the 85 positive terminals of the translating devices 22, which have their negative terminals connected with the negative side of the generator through the lead 23. 24 is a storage battery connected across leads 21 and 23 90 through the solenoid 13, which is preferably of coarse wire adapted to carry the full charging or discharging current of the battery; while the portion of such current that shall circulate through the coil 13 may be adjusted as by the variable resistance 25 in shunt thereto. The solenoid 12 is preferably of fine wire and in shunt across the generator, as indicated, and has in series therewith, for the purpose of adjustment, the variable resistance indicated at 26. The arrangement of the solenoids 12 and 13 with respect to the core 11 may or may not be such as diagrammatically portrayed 100 in the drawing, but may be any relation- 110

ship possessed of the characteristics intended to be schematically indicated by the drawing, which relationship is such that when the coil 13 alone is excited, regardless of the direction of current therethrough, it will either draw core 11 downwardly or else not tend to move the core at all or else tend to lift the same to a negligible extent; while the combined action of coil 13 and coil 12, when both excited and the generator is supplying the battery, is to tend to raise core 11 upon increase of excitation of either or both coils. And it will be noted that, with the arrangement shown in the drawing, if properly constructed with respect to its operative conditions, the relationship above outlined may be maintained. That is, the coil 13 is shown somewhat below the center of the core 11 and, therefore, when operating alone and energized in either direction, it will tend to draw the core 11 downwardly and increase the pressure upon the pile 3. It is so arranged with respect to coil 12 that when the generator is supplying current to the battery the magnetomotive forces of the coils 12 and 13 are in the same direction, and, therefore, the two coils act in a manner somewhat similar to a single solenoid or coil tending to lift the core 11 and decrease the pressure upon the pile 3. Therefore, current from the battery to the translating devices while the generator is operating sets up a magnetomotive force opposed to that of the coil 12 tending to cause the core 11 to move downwardly and increase the pressure upon the pile 3, which it continues to do after the generator stops and current in coil 12 ceases. If the coil 13 be placed around the middle portion of the core 11, the action will be the same except that 13 when energized alone will not tend to move the core 11 appreciably in either direction; while if the coil 13 be placed slightly above the center of the coil 11, it may tend to raise the same somewhat when energized alone. And my invention pertains particularly to placing the coil 13 in such position that when energized alone it will not tend to raise the core 11 so as to affect the pile 3 in such manner as to increase its resistance appreciably, even when the full load is upon the battery. And, therefore, my invention provides a means whereby the entire battery current to the translating devices may circulate through the coil 13 without interfering with the "picking up" of the generator field, even though the generator be started at a time when a greater current is flowing to the translating circuit from the battery through coil 13 than is supplied by the generator through the coil 13 and limited by the said coil cooperating with the coil 12 when the generator is operating.

55 Switch 20 is preferably one of the auto-

matic variety adapted to close its circuit when the generator voltage is substantially equal to or slightly in excess of that of the battery and to open its circuit when the generator voltage is substantially equal to or very slightly below that of the battery, in such manner as to prevent back discharge through the generator. And as such switches are well known in the art and the particular type chosen forms no part of my present invention, the mere presence of such a switch is indicated, and details of construction are purposely omitted for the sake of clearness, it being understood that any suitable type of such switch may be used.

50 In that system shown in Fig. II, like numerals indicate like parts, and the only differences intended to be brought out by the use of this figure are the addition of a current responsive means adapted to affect the resistance of the carbon pile 3 in response to fluctuations in the total generator output, and that all of the responsive means may be mechanically disconnected from the lever 6 and its cooperating parts so as to be entirely independent thereof, except at such times as performing a regulating function. In this figure the generator current responsive means is shown as comprising a current coil 27 in the generator circuit, and a voltage coil 28 across the generator which may cooperate with the coil 27 in a manner similar to the cooperation between coils 12 and 13. In Fig. III, the coils 27 and 28 are replaced by the coil 29 in series with the generator circuit.

55 An operation of my invention is substantially as follows:

If the generator be at rest or have its armature revolving at low speed, switch 20 will be open and the translating devices may be supplied by the battery 24 in a well known manner, the current from the battery passing entirely or in part through the solenoid 13, as may be adjusted by means of the variable resistance 25. This current to the translating devices will tend to draw the core 11 downwardly and increase the pressure upon the pile 3, so as to lower the resistance thereof and cause the generator to be capable of picking up at very low speed.

60 If the generator speed now increase until its voltage is in excess of that of the storage battery, switch 20 will close and current will flow from the generator to the battery 120 and translating devices, that portion supplied to the battery traversing the coil 13 in a reverse direction to the current supplied by the battery to the translating devices. Current will also flow through the voltage coil 12, which is across the generator. And I usually so adjust the operation of the coils 12 and 13 that when the voltage across the battery is substantially or in the neighborhood of its normal charging voltage, with 125

a desired charging current passing through the coil 13, the combined action of the two coils will be such that, if the voltage remain substantially constant and too great a charging current should tend to flow, the said current will not be allowed to exceed a predetermined chosen limit, as the core 11 will be raised so as to lift the lever 6 and decrease the pressure upon the pile 3 so as to prevent this maximum current from being exceeded. By properly proportioning and arranging the coils 12 and 13, the current delivered to the battery may be more or less varied with reference to the condition of the battery, as indicated by its voltage. For, as the battery voltage rises, as for example due to charging, a greater voltage will be maintained by the generator and coil 12 will become somewhat stronger. And, therefore, the current necessary in the coil 13 to affect the generator regulation will be somewhat less, and will diminish somewhat as the voltage across the battery rises. This may be taken advantage of, under certain conditions, when it is desirable. However, it is within my invention to use any means desired to maintain a constant voltage across the solenoid 12, if it be desired that the maximum battery charging current shall always be of fixed value. If at any time the voltage across the generator tend to exceed a predetermined desirable limit, I so adjust the operation of the coil 15 that it will then raise its core and bring the rod 17 into contact with the lever 6 and prevent this desired maximum voltage from being exceeded. Therefore, if the generator be regulated in response to voltage fluctuations by the voltage coil 15, and the battery voltage rise so as to more and more nearly approach the value held constant by the said voltage coil, the current to the battery will naturally fall off and approach zero as the generator and battery voltages approach each other. However, should the battery voltage at any time reach a sufficiently low value that the generator will tend to deliver thereto too great a charging current, the same will be prevented by the operation in response to coil 13 cooperating as it does with the coil 12 to affect the core 11. If, while thus operating to charge the battery and supply the translating devices the generator have its speed cut down, it will reach a point where a part of the current will be supplied by the battery and part by the generator; and, notwithstanding the voltage across the generator may be almost the normal voltage, coil 12 will be prevented from materially tending to lift the core 11 as the current supplied to the lamps through coil 13 will be in a reverse direction, weakening or tending to nullify the effect of coil 12. If the generator speed continue to fall, the voltage across 12 will, of course, fall, and the coil

will become weaker and approach zero, and at a certain point the combined effect of the coils 12 and 13 will be to pull the core 11 downwardly so as to tend to decrease the resistance 3 and maintain the generator 70 at as high voltage as possible for its speed at that time.

An operation of that system shown in Fig. II is substantially the same as that outlined above with respect to Fig. I, with the exception that there will be no downward pulling effect exerted by the core 11 upon the lever 6, as the said core is not connected therewith but so arranged as to raise the lever by contact therewith when the windings lift 80 the core 11. And if at any time the generator total output tend to exceed a predetermined limit, coil 27 will raise its core 30 so as to bring the member 31 into contact with the lever 6 and prevent the total generator output from exceeding this predetermined limit, which limit in Fig. II may be modified in accordance with the voltage upon coil 28, if desired; while at all times the battery charging current will 90 be prevented from exceeding a predetermined limit by coils 12 and 13, as outlined with respect to Fig. I, and the voltage will be held from exceeding a predetermined limit by coil 15, as also outlined with respect to Fig. I, and at no time will the current flowing from the battery to the lamps affect the resistance controlling the generator in such manner as to prevent the proper picking up of the generator at low speed. It will be 100 obvious that the core 11 of Fig. I may have the rod 10 disconnected from the lever 6, as shown in Fig. II, in which event current flowing from the battery to the lamps cannot tend to compress the pile. However, it 105 will not interfere with the other instrumentalities adapted to compress the pile, regardless of the strength of the current in said coil. And it will further be obvious that the core 11 of Fig. II might be united with 110 the lever 6, as indicated in Fig. I, if desired.

An operation of that modification shown in Fig. III will be the same as that of Fig. II, with the exception that core 30 will be affected only by the generator current in the coil 115 29, irrespective of any voltage coil.

From the foregoing it will be noted that I have produced a system having the advantages of the usual systems employing an automatic current regulator responsive to 120 fluctuations in current in the battery charging circuit, but not suffering the draw-back met with in most such systems wherein the current supplied by the battery to the translating devices when the generator is at rest 125 tends to increase the field resistance in such manner as to tend to interfere with the proper building up of the generator field at low speed, and that I accomplish this without contacts or switching means or such 130

equivalents for shunting current away from the battery current responsive mechanism as are often used for this purpose.

I do not wish in any way to limit myself to any of the exact details of construction or operation given above to illustrate an embodiment of my invention, for it will be obvious that wide departure may be made therein without departing from the spirit and 10 scope thereof.

What I claim is:

1. The combination with regulating means and a magnetic member for affecting the same, of means for energizing said member 15 capable of alone producing like regulating effects thereupon regardless of the direction of excitation, and means incapable of alone operating the regulating means cooperating to assist said energizing means in affecting 20 said member to affect the regulating means when the energizing means is excited in one direction only, said energizing means, when so assisted, affecting the regulating means in a direction opposed to its effect thereupon 25 alone.

2. The combination with a generator, regulating means therefor, a storage battery, and a translation circuit, of means for controlling the regulating means comprising a movable 30 member, a plurality of coils cooperating to magnetize said member and so connected and arranged with respect to said member that current flowing into the battery from the generator through one of said coils tends to 35 cause the generator output to be decreased and current flowing from the battery through said coil to the translation circuit always tends to affect the regulating means in the direction that causes the generator field to be 40 increased.

3. The combination with a generator, of a regulator having a plurality of actuating coils and means cooperating therewith whereby when one coil is inert the other coil 45 tends to increase the generator output and when both coils are energized their mutual effect tends to limit the generator output.

4. The combination with a dynamo, storage battery, and translating devices, of 50 means for regulating the dynamo comprehending a regulating device, operating means therefor comprising a coil in circuit with the battery affected in one direction when the dynamo is charging the battery 55 and in an opposite direction when the battery is supplying the translating devices, means influenced by said coil to affect the regulating device, said coil and said means alone being ineffective to appreciably reduce 60 the activity of the dynamo, regardless of the magnitude of the effort exerted thereby, and means cooperating therewith to affect the regulating device to reduce the activity of the dynamo only when the dynamo is sup- 65 plying current.

5. The combination with a generator, storage battery, and translating circuit supplied thereby, of means for regulating the generator in response to fluctuations in the battery charging current and, in another sense, 70 in response to the battery discharging current, and independent means cooperating therewith to affect the regulating means in response to the total generator output.

6. The combination with a generator and 75 storage battery, of a regulator for the generator, means for controlling the regulator comprehending a core of magnetic material, a coil in series with the battery and surrounding said core, the position of said coil 80 with respect to said core being such that current flowing to and from the battery is ineffective to move the core to appreciably reduce the activity of the generator, a coil wound about said core and so energized and 85 related to said core that it cooperates with the first named coil and both coils thus cooperating work together to limit the activity of the generator when the current in the first named coil is flowing from the generator to 90 the battery.

7. The combination with a generator and storage battery, of a regulator for the generator, means for controlling the regulator comprehending a core of magnetic material, 95 a coil in series with the battery and surrounding said core, the position of said coil with respect to said core being such that current flowing to and from the battery is ineffective to move the core to appreciably reduce the activity of the generator, a coil wound about said core and so energized and 100 related to said core that it cooperates with the first named coil and both coils thus cooperating work together to limit the activity 105 of the generator when the current in the first named coil is flowing from the generator to the battery, and independent responsive means adapted to cooperate with said coils to limit the voltage of the generator and, in 110 cooperation with the second coil above mentioned, control the entire regulation of the generator when the battery becomes charged and the current in the first named coil falls off to an inappreciable value.

8. The combination with a generator, storage battery, and translating devices supplied thereby, of means for regulating the generator in response to fluctuations in the battery charging current and, in another sense, 115 in response to battery discharging current, and independent means cooperating therewith to affect the regulating means in response to voltage fluctuations and dominating in the regulation of the generator when 120 its voltage reaches a predetermined limit.

9. The combination with a source of electrical potential difference, regulating means therefor, a storage battery and translating circuit supplied thereby, of means for con- 125 130

trolling the regulating means comprising a
movable member, a plurality of coils cooper-
ating to magnetically affect said member and
so connected and arranged with respect
thereto that current flowing into the battery
from the source, through one of said coils,
5 tends to cause the electrical potential differ-
ence at said source to be decreased, and cur-
rent flowing through said coil from the bat-
tery to the translating circuit always tends 10
to cause the regulating means to tend to in-
crease the value of the electrical potential
difference at said source.

JOHN L. CREVELING.
